MANHOLE FRAME AND COVER

Michael W. Merriman, Cleveland, Ohio

Application March 30, 1929, Serial No. 351,263

4 Claims. (Cl. 94—34)

This invention relates to improvements in manhole frames and covers, and a method of casting the same whereby true and accurate engaging surfaces between the frame and cover are provided without machining, and whereby the metal at these surfaces is hardened so as not to be worn down materially by the vibration and other relative movements between the frame and cover, due to the passage of traffic thereover.

10 Another object is to improve the frame of the manhole by hardening that portion thereof which has to withstand the heavy blows of traffic.

Other objects and features of novelty will appear as I proceed with the description of that embodiment of the invention which, for the purposes of the present application, I have illustrated in the accompanying drawing, in which:

Fig. 1 is a plan view of a manhole frame and cover in which the invention may be incorporated.

20 Fig. 2 is a vertical central sectional view of the same.

Fig. 3 is a fragmental sectional view, more or less diagrammatic in character, illustrating a method of casting the frame member in accordance with the invention.

In the drawing, a manhole frame 10 of circular contour is illustrated, this frame having a bottom flange 11 which is connected with the upstanding wall of the frame by vertical webs 12. This frame is intended and adapted to be set into a street pavement, the upper surface 13 being exposed and being substantially flush with the surface of

35 On the inner side of the frame, somewhere below the top thereof, there is formed an integral ledge 14. The upper periphery of this ledge is separated from the manhole of the frame by an annular groove 15. The metal at and just below the top surface 16 of the ledge is chilled. This 40 surface constitutes the seat for the cover. The metal at and just below the surface 13 is also chilled.

A circular cover 17, which is deepened at the center and periphery, is formed to fit within the frame, suitable side clearance being provided so as to make the removal of the cover a matter merely of lifting the same. The lower peripheral surface 18 of the cover is formed to fit upon the seat 16, these two surfaces being preferably flat or conical. The metal of the cover at the surface 18 is chilled.

In Fig. 3 I have indicated at 19 the sand of a mold for casting the frame member 10. In this figure a fragment of the block pattern is shown at 20. It is placed in the flask right side up.

Upon the surfaces of the pattern which correspond to surfaces 13 and 16 of the casting are placed ring-shaped iron chills 21 and 22 respectively. The flask is then filled with sand and tamped, after which it is inverted, the pattern withdrawn, and a sand core shaped to produce the internal surface of the frame inserted. When the metal is poured into the mold, that portion of it which comes in contact with the chills, naturally conforms exactly with the surfaces of the chills and, of course, is hardened. The cover 17 is cast in a similar manner, except that one chill ring only is employed since there is but one chilled surface to produce.

I exercise considerable care in the making of 15 the chill 22 and that for the surface 18, to insure the production of true and accurate surfaces for contact with the molten iron, and I subject them to inspection after each casting operation in order to make sure that they remain accurate. Those which become warped in use are either refinished or discarded. Hence, the surfaces 16 and 18 of the two castings which have been formed by engagement with the accurately maintained surfaces of the chills, are 25 themselves accurate and true, and a nice fit is insured. Accordingly, when a vehicle passes over the cover, there is very little, if any, movement, and no audible noise. Wear is negligible both because of the absence of movement and 30 because of the hardness of the engaging surfaces. The groove 15 is of some importance in the casting of the frame member, inasmuch as it separates the chilled cover seat from the main wall of the casting.

While, in the foregoing specification, I have described the invention with reference to a manhole frame and cover, it is obviously applicable to other articles of a more or less similar nature, particularly those in which an accurate 40 seating of the cover is desirable.

Having thus described my invention, I claim:

1. In combination, a frame comprising an annular cover seat of chilled iron, an enclosing wall surrounding said seat, said wall being spaced 45 from the seat, and a cover having an annular chilled iron surface formed for engagement with said seat, whereby hardened, accurate engaging surfaces may be provided.

2. A method of providing true and accurate 50 engaging surfaces in an iron frame and cover, which consists in casting said frame and cover in sand molds containing chills with accurately formed surfaces complementary to the engaging surfaces of the castings.

3. In combination, a frame comprising a cover seat of chilled iron, and a cover having a chilled iron surface formed for engagement with said seat, whereby true engaging surfaces may be provided without machining.

5

4. In combination, a frame comprising a cover seat of chilled iron, and a cover having an annular chilled iron surface formed for engagement with said seat, whereby hardened, accurate engaging surfaces may be provided.

MICHAEL W. MERRIMAN.
